UNITED STATES PATENT OFFICE.

JOHN SCHIERENBECK, OF ALBANY, NEW YORK.

EGG-MARKING DEVICE.

Application filed August 19, 1926. Serial No. 130,270.

This invention relates to the class of marking and printing machines and devices, and has particular reference to machines and devices for marking or impressing on delicate articles difficult to handle and which break easily when subjected to more than slight pressure, such as eggs for instance.

Some of the objects of the present invention are: to produce a machine or device of the indicated character having novel features of construction and operation whereby delicate articles of merchandise such as eggs may be marked, printed or impressed with suitable indicia such as the year, month and day to constitute a date or matter of record, or any other indicia; to accomplish these ends expeditiously and without loss as the result of breakage; and to provide means in a machine or device of the indicated character combined with the marking or impressing means which will conform to curved surfaces of objects or merchandise to be marked or to be impressed with suitable matter, which conforming means also provides the necessary cushion in the obtainment of the desired coactive pressure in the marking or impressing operation.

With the foregoing and still other objects in view, the invention resides in the particular provision, construction, relative disposition and operation of the parts hereinafter fully described and illustrated in the accompanying drawings, in which

Figure 1 is a perspective view of the device embodying the present invention.

Fig. 2 is a central vertical sectional view through the device.

Fig. 3 is a sectional view illustrating the means by virtue of which the type bands are permitted to be adjusted with respect to each other.

Fig. 4 is a sectional elevation, the section being taken on the line 4-4 of Fig. 2.

Fig. 5 is a sectional view taken on the line 5-5 of Fig. 2.

Fig. 6 is a sectional view illustrating the manner in which an egg is marked.

Fig. 7 is a view illustrating the particular type of mark impressed by the device on one end of an egg.

Generally stated, the device or machine of the present invention comprises a casing in which is arranged a pair of flexible type bands of any suitable material which embody suitable indicia, conformable elastic

means which coacts with portions of the bands for making the particular marks or impressions when subjected to pressure by virtue of the indicia, and inking mechanism for applying ink to the indicia.

Referring now more particularly to the several views of the drawing, it will be apparent that the casing 10 is of rectangular construction and is provided with a substantially circular opening 11 in the front wall thereof. Arranged within the casing 10 is a suitable frame structure 12 which rests on the bottom wall of the casing. The frame structure 12 includes sides having portions 13 and 14.

The bands hereinbefore referred to are designated 15 and 16. The band 15 will be made preferably of flexible material such as rubber. The band 15 on one side thereof is provided with a series of sections 17, also of rubber. The sections 17 are spaced equidistantly and each is provided on the front face thereof with suitable type 18. In the present instance there are 12 sections 17 and each has numerals denoting a calendar year, and letters denoting a particular month of the year denoted. One end of the band 15 is secured to and adapted to be wound on and unwound from a spool 19 secured to an arbor 20 mounted in the juncture of the portions 13 and 14 of each of the sides of the frame 12. One end of the arbor 20 extends through one side of the casing 10 and has a knurled knob 21 secured thereto. The opposite end of the band 15 is secured to and is adapted to be wound and unwound from a spool 22 secured to an arbor 23 mounted for rotation in suitable bearings carried by the portion 14.

One end of the arbor 22 extends through the side of the casing hereinbefore mentioned and has secured thereto a knurled knob 24. By manipulating the knobs 21 and 24, the band 15 may be moved or adjusted to any desired extent so as to bring any desired section 17 adjacent the opening 11 in a printing position. Portions of the band 15 having the sections 17 secured thereto respectively are provided with openings which register with similarly shaped openings in the section 17, the openings being designated 25.

The band 16 will be made from material similar to that from which the band 15 is made and is provided with a series of sections 26 on one face thereof. The sections 26 are made from material similar to that 116

from which the sections 17 are made and one face of each section is provided with type 27. The type 27 is in the form of numerals which denote particular days of the month. Each section 26 is adapted to be received in either of the openings 25 and is of a thickness to bring about a printing relationship of the type 27 with the type 18. The type 18 and 27 will combine to denote a particular year, month and day as shown for instance in Fig. 7, in which is represented an egg with the date May 7, 1926. One end of the band 16 is secured to and is adapted to be wound on and unwound from a spool 28 secured to an arbor 29 mounted for rotation in suitable bearings carried by the portions 14 of the sides of the frame 12. One end of the arbor 29 extends through one side of the casing 10 and has secured thereto a knurled knob 30. The opposite end of the band 16 is secured to and is adapted to be wound on and unwound from a spool 31 secured to an arbor 32 mounted for rotation in suitable bearings carried respectively by the portions 14 of the sides of the frame 12. One end of the arbor 32 extends through one side of the casing 10 and has secured thereto a knurled knob 33. By manipulating the knobs 30 and 33 the band 16 may be moved or adjusted to any desired extent to bring any particular one of the sections 26 adjacent the opening 11. A lead 34 of the band 15 is maintained substantially vertically disposed by a guide roller 35 arranged on a spindle 36 secured between the portions 13 of the frame 12 and a trapezoidal member 37 secured to an arbor 38 mounted for turning movement in suitable bearings carried by portions 13 of the frame 12. One end of the arbor extends through one side of the casing 10 and has secured thereto a knurled knob 39. When the member 37 is moved to the position shown in Fig. 3, the lead 34 of the band 15 will be moved from its vertically disposed position at an angle for a purpose to appear. The band 16 passes around suitable guide rollers 40 arranged between the portions 13 of the frame 12. The rollers 40 maintain a lead 41 of the band 16 adjacent the lead 34.

In order to provide means for setting up a cushion action in conjunction with two of the type sections 17 and 26 at the opening 11 in the casing, and so as to conform with a particular formation of an object or thing to be marked or have applied thereto an impression from the type characters or indicia embodied by the particular sections 17 and 26, there is provided in the present instance a conformable elastic element in the form of an inflated rubber ball or sphere 42. The ball 42 is supported by a dished member 43 secured as at 44 to a bracket 45 carried by the portions 14 of the frame 12. It is to be noted that the

point of attachment of the ball 42 is diametrically opposite the point at which the particular type sections 17 and 26 are disposed, which serve in the marking or printing operation. A portion of the ball 42 constantly acts on the lead 41 of the band 16 and has a normal tendency to hold the lead flexed toward the lead 34. By virtue of this condition any particular type section 26 will be releasably maintained in one of the openings 25, as shown most clearly in Figs. 2 and 6.

The inking mechanism hereinbefore referred to for applying ink to correlated type sections 17 and 26 in the present instance includes an ink pad 46 which will be saturated with some suitable ink. The ink pad 46 is carried by an arm 47 supported for rocking movement on a shaft 48, whose opposite ends are mounted respectively in suitable fixed bearings 49. The shaft 48 has connected thereto an arm 50, which is pivotally connected to a member 51, and the latter is also pivotally connected to an arm 52. The arm 52 is suspended from one end of the arbor 20 as at 53, and is also provided with a weight 54. The weight 54 constitutes a means for normally maintaining the ink pad 46 in an inking position as shown in full lines in Fig. 2. A push rod 55 is provided and has pivotal connection as at 56 to the arm 52 and extends through the front wall of the casing 10, and the free end thereof is provided with a knob 57. By pushing inwardly on the knob 57 and through the intervention of the parts connected to the rod 55, the ink pad 46 will be moved to the position shown in dotted lines in Fig. 2 uncovering the correlated type sections 17 and 26 previously inked, so that the article to be marked or to be printed on, such as the egg E may be pressed in contact with the correlated type sections 17 and 26. In this way a great many eggs may be marked with a particular date rapidly in succession without any loss due to breakage, due to the particular provision of parts hereinbefore described. The operation is thought to be fully understood and not to require a more extended explanation.

It is to be understood that the invention is not restricted to the precise arrangement of parts shown and described, as details of construction may be modified and rearranged without departing from the spirit of the invention, the scope of which is limited only by the terms of the appended claims.

I claim:

1. In a marking device, correlated type bands, a yieldable and conformable element associated with portions of said bands, said element coacting with the type sections of the bands to make an impression, and means for inking said type sections comprising an

ink pad, and a weighted lever arrangement operable to move said pad into and out of contact with said type sections.

2. In a marking device, correlated type bands, an inflated spherical element associated with portions of said bands, said element coacting with type sections of the bands to make an impression, and means for inking said type sections comprising an ink pad, and a weighted lever arrangement operable to move said pad into and out of contact with said type sections.

3. In a marking device, flexible bands, means supporting the bands for adjustment with respect to each other, one of said bands having type sections at intervals, the band and said type sections having registering openings therein, the other band having type sections adapted to enter said openings so as to combine with the first mentioned type sections to produce a suitable mark or impression.

4. In a marking device, flexible bands, means supporting the bands for adjustment with respect to each other, one of said bands having type sections at intervals, the band and said type sections having registering openings therein, the other band having type sections adapted to enter said openings so as to combine with the first mentioned type sections to produce a suitable mark or impression, and inking mechanism for inking said type sections.

5. In a marking device, flexible bands, means supporting the bands for adjustment with respect to each other, one of said bands having type sections at intervals, the band and said type sections having registering openings therein, the other band having type sections adapted to enter said openings so as to combine with the first mentioned type sections to produce a suitable mark or impression, inking mechanism for inking said type sections, said inking mechanism including an ink pad, and means for effecting the movement of the ink pad into and out of contact with said type sections.

6. In a marking device, flexible bands, means supporting the bands for adjustment with respect to each other, one of said bands having type sections at intervals, the band and said type sections having registering openings therein, the other band having type sections adapted to enter said openings so as to combine with the first mentioned type sections.

tions to produce a suitable mark or impression, inking mechanism for inking said type sections, said inking mechanism including an ink pad, and means for effecting the movement of the ink pad into and out of contact with said type sections and for normally holding the ink pad in contact with particular type sections of the bands.

7. In a marking device, flexible bands, means supporting the bands for adjustment with respect to each other, one of said bands having type sections at intervals, the band and said type sections having registering openings therein, the other band having type sections adapted to enter said openings so as to combine with the first mentioned type sections to produce a suitable mark or impression, inking mechanism for inking said type sections, and a conformable elastic element juxtaposed with respect to portions of said bands so as to coact with particular type sections thereof respectively to make a mark or impression.

8. In a marking device, flexible bands, means supporting each of the bands for movement, means for effecting the operation of the supporting means to cause the movement of each of the bands, said supporting means maintaining portions of the bands disposed side by side, each band having type sections, the type sections of one band adapted to combine with the type sections respectively of the other band to constitute a series of different marks, a conformable elastic element positioned to coact with particular type sections, and means for inking said type sections comprising an ink pad, and a weighted lever arrangement operable to move said pad into and out of contact with said type sections.

9. In a marking device, flexible bands, means supporting each of the bands for adjustment, one of said bands having openings therein, each of said openings surrounded by a type section, the other band having type sections each adapted to fit in either of said openings, means for holding particular type sections of said bands associated, means for holding a portion of one band away from the adjacent portion of the other band to permit of the relative adjustment of the bands, and means for effecting the relative adjustment of the bands.

JOHN SCHIERENBECK.
